METHOD AND APPARATUS FOR CONTROLLING THE LOAD-SPEED CHARACTERISTICS OF MOVING SYSTEMS

Application filed June 11, 1928. Serial No. 284,369.

My invention relates to a method and apparatus for controlling the load-speed characteristics of one or more moving systems.

In accordance with my invention there is utilized a speed-responsive device and a load-responsive device which jointly effect a control to modify the normal load-speed characteristic of a moving, work-producing unit; more specifically, a frequency-responsive device and a load-responsive device, as a wattmeter, jointly effect control of the prime mover of an alternator, as a turbine, by controlling the flow of steam to the blades of the turbine rotor.

Further in accordance with my invention, in a group of moving systems, as for example, of alternators operating in parallel, having a common load, there are utilized control mechanisms to effect a predetermined distribution of load between the several units, more specifically and preferably, the control mechanisms are jointly responsive to change of load and frequency to effect distribution of the total load between them in a predetermined manner, the load on the individual units being a function of the total load.

My invention resides in a method and apparatus of the character hereinafter described and claimed.

For an understanding of my method, and for an illustration of some of the various forms my invention may take, reference is to be had to the accompanying drawings in which:

Fig. 1 is a diagrammatic view of apparatus suitable for practicing my method and embodying my invention in one of its forms.

Fig. 2 is a fragmentary perspective view of recording and control mechanism utilizable in accordance with my invention.

Fig. 3 is a diagrammatic view of a system according to my invention.

Fig. 4 is a view similar to Fig. 3, illustrating a modification.

Figs. 5, 6 and 7 are curves referred to in the explanation of distribution of total load between several units of the system of Fig. 3.

Referring to Fig. 1, A is an alternator or source of alternating or fluctuating current,

whose load-frequency characteristic is modified in any desired manner.

Its terminals are connected respectively to the variable contacts 1 and 2 constituting conjugate points of a Wheatstone bridge, whose other conjugate points are the points of engagement of contacts 3 and 4 movable along the slide wires or adjustable resistances S and S₁, respectively. In the first bridge arm is included a condenser C shunted by the non-inductive resistance r; in series with that portion r₄ of the non-inductive resistance S lying to the left of contact 3 and that portion of non-inductive resistance r₁₂ above contact 1. In the second bridge arm are included the condenser C₂, non-inductive resistance r₅ and that portion of the non-inductive resistance r₁₃ above contact 2 and the non-inductive resistance S to the right of contact 3. In the third bridge arm are included the non-inductive resistance r₆, that portion of r₁₂ below contact 1 and the portion r₇ of the slide-wire resistance S₁ to the right of contact 4. In the fourth bridge arm are the resistances r₈ constituting the remainder of the resistance S₁ to the left of contact 4, that portion of r₁₃ below contact 2 and the non-inductive resistance r₉.

In case the resistances S and S₁, which may be in the form of simple wires or in the form of helices along which contacts 3 and 4 may move, are not of themselves exactly correct in value, they may, as well understood in the art, be shunted by resistances such as r₁₀ and r₁₁, respectively, to insure between their terminals exactly the correct or desired amount of resistance.

Resistance units r₁₂ and r₁₃ may be so constructed that movement of contacts 1 and 2 effects a uniform increase or decrease of resistance. However, either or both, may be so constructed that equal increments of contact movement effect dissimilar or varying increments of resistance for a portion, or portions of, or the whole of, the range of contact movement, for a purpose hereinafter described.

It is desirable that all of the resistances aforementioned shall have small or substantially zero temperature co-efficient, to avoid

influence of temperature upon the measurements.

While the source A is in one conjugate conductor of the bridge, in the other, between the contacts 3 and 4, is connected the movable coil 20 of a galvanometer having the deflecting pointer or needle 19. The coil winding may, as well understood in the art, be shunted by a resistance r_{20} , of suitable magnitude.

10 The alternating magnetic field of the galvanometer is produced by current from source A traversing the galvanometer field winding A or coil f , in series with which may be connected the resistance r_{14} .

15 The phase angle of the current exciting the galvanometer magnet winding f with respect to the impressed electromotive force may change or vary from various causes, such as, for example, temperature changes of winding f , etc. Such a change of phase of the field-exciting current will introduce error in the measurements unless means are provided to make possible a true balance of the bridge regardless of the shifting of phase of the field-exciting current of the galvanometer. To this end it is essential that three ratios shall be equal for all frequencies within the frequencies to be employed. This equality of ratios is expressed by the following equation:

$$30 \quad \frac{r_1}{r_2} = \frac{d_1}{d_2} = \frac{a}{b} \dots 1$$

in which r_1 and d_1 are, respectively, the resistance and reactance components of one arm of the bridge, as, for example, the aforesaid first arm including C_1 , r , r_4 , etc.; r_2 and d_2 are, respectively, the resistance and reactance components of another arm of the bridge, for example, the aforesaid second arm, including r_3 , r_6 , C_2 etc.; and a and b are, respectively, the resistances or impedances of the other arms of the bridge.

In the illustrative example, where capacitative reactances or condensers are employed, it is desirable that they be low loss condensers, to avoid phase angle or capacity changes with temperature changes, and are preferably mica condensers of the best type.

50 The combination of a condenser, as C_1 , with a shunting resistance, as r , is the equivalent and has the characteristics of a condenser having considerable losses, which may be expressed in terms of an equivalent resistance which changes in magnitude with changes in frequency. Accordingly, the aforesaid resistance r_1 is an apparent, fictitious or equivalent alternating current resistance, which changes in magnitude with changes in frequency, and comprises not only the resistances r , r_4 , and a variable portion of r_{12} , but, in addition, the apparent resistance corresponding with the losses, if any, of the condenser C_1 , per se, and of the combination of the condenser C_1 with its shunting resistance. The aforesaid resistance r_2 corre-

sponds with the sum of the resistances r_3 and r_6 and the apparent resistance, variable with frequency, due to losses of condenser C_2 , if any.

70 From equations

$$r_1 = \frac{r}{1 + w^2 c^2 r^2} + r_4 + r_{12} \dots$$

$$d_1 = \frac{w c r^2}{1 + w^2 x^2 r^2} \dots$$

$$d_2 = \frac{1}{w y} \quad w = \text{omega}$$

well known to those skilled in the alternating current art, and in which w (omega) is 2π 80 frequency, x and y are, respectively, the capacities of condensers C_1 and C_2 , and r , r_4 and r_{12} are the magnitudes of r , r_4 and that portion of r_{12} included in the first arm of the bridge, are determinable the proper values of the several resistances and capacities to be utilized in an arrangement such as indicated in Fig. 1, for use within a desired range of frequencies, it being understood that contacts 3 and 4 are moved in unison with each other 90 because attached to the same movable member C.

For a given position of contacts 1 and 2, the contacts 3 and 4 take a different position for each different frequency, in order to balance the bridge for that frequency, in which event the galvanometer coil 20 is in its zero or non-deflecting position.

95 From the foregoing it will be understood that the function of the slide-wire S_1 is to change the ratio of the resistances in the third and fourth arms of the bridge in proportion to the change in the ratio of effective resistance and reactance in the first and second arms of the bridge in order that the equality of ratios expressed in equation (1) shall obtain, whereby the bridge may be truly balanced regardless of changes of the phase angle in the galvanometer field.

100 Referring to Fig. 2, M is an electric motor or other suitable source of power rotating the shaft 5 at substantially constant speed. A lever 6 is pivoted at its upper end on a horizontal axis and has pivoted thereto on a horizontal axis at its lower end the arm 7, on each end of which is a shoe 7a, of cork or the like, frictionally engaging the rim 8 of the clutch disk or wheel 9, secured upon the shaft 10 of the movable structure or system. Secured upon the shaft 5 is a cam 11, which periodically engages the lever 6 and moves it outwardly, in opposition to a spring, not shown, thereby lifting the shoes 7a from the rim 8, the spring returning the shoes into engagement with the rim after predetermined rotation of the cam 11. Upon the shaft 5 is secured a second cam 12, which, after the shoes have been lifted from the rim by the cam 11, actuates the finger 13 on the lower end of the arm 14 secured at its upper end to

110

115

120

125

130

the member 15 pivoted on a horizontal axis at 16. Upon the member 15 is secured the member 17, whose upper edge 18 is inclined outwardly from the center. Disposed immediately above the edge 18 is the aforesaid needle or pointer 19 of the alternating current galvanometer whose coil is 20. At the opposite ends of the member 17 are the abutments 21 for limiting the deflection of the needle 19. Directly above the needle 19 and beneath which it normally freely swings are the edges 22, preferably straight and horizontal, upon the members 23, 23, pivoted at 24, 24, and extending toward each other, leaving a gap of sufficient width between their inner ends for free entry of the needle 19 when in balanced or zero position, corresponding with a balance of the Wheatstone bridge of the character shown in Figs. 1, 4 and 6. The needle 19 normally swings freely between the edge 18 and the members 23, 23, which latter have downwardly extending arms biased toward each other by the spring 26. Attached to the lower end of the arm or lever 6 is a triangular plate 27 carrying the pins 28, 28, co-operating with the lower ends of the members 23, 23. At opposite ends of the arm 7 are the lugs 29, 29, adapted to be engaged by the cams 30, 30, similar in shape and similarly positioned and secured upon the shaft 5.

As the galvanometer needle 19 deflects in the one direction or the other, the shaft 10 will be rotated in the one direction or the other, and to an extent corresponding to the extent of the galvanometer deflection. For example, when the needle 19 deflects to the right, Fig. 2, it is clamped, due to periodic vertical movement of member 15 by cam 12, between the inclined edge 18 and the lower edge 22 of the right-hand member 23, causing the member 23 to be tilted in a clockwise direction about its pivot 24, thereby pushing the right-hand pin 28 on plate 27 and so tilting the movable driving clutch arm 7 in a clockwise direction while cam 11 is holding shoes 7a, 7a from the rim 8 of a clutch wheel 9, the angular movement of the member 7 being dependent upon the degree of deflection of needle 19. The cam 11 soon thereafter allows the shoes to grip again the rim 8 of wheel 9 and soon thereafter the left-hand cam 30 engages the ear 29 of arm 7, which has been elevated, pushing it downwardly due to rotation of shaft 5, to restore it to the horizontal position indicated, but in so moving back to normal position, the clutch member rotates the disk 9 and shaft 10 affixed thereto in a counter-clockwise direction.

Secured upon the shaft 10 is a disc 31 of insulating material, carrying upon its periphery the aforesaid resistances or impedances S, S1, which in this example, as indicated in Fig. 3, are rotated, while their co-acting contacts 3 and 4 are stationary. Secured upon

the shaft 10 is a second disc 32 carrying the arcuate contacts 33 and 34, with which co-acts the stationary contact or brush 35. The discs 31 and 32 are adjustable to any suitable angles with respect to each other and with respect to the shaft 10 by suitable set screws 36 and 37.

Secured upon the shaft 10 is the grooved pulley wheel 38, around which is wrapped the cord 39, which passes over the idler rollers 40 and has attached thereto the pen or marker 41 for drawing upon the record sheet or paper 42. The paper 42 is driven by the motor M, as well understood in the art.

Referring to Fig. 1, the movable structure or system of Fig. 2 is shown insofar as it comprises the shaft 10 and the discs 31 and 32. The slide wires S, S1 are comprehended in a Wheatstone bridge of the character indicated in Fig. 1. The combination of the Wheatstone bridge and the apparatus of Fig. 2 may be termed an electro-mechanical system which is balanced at a frequency determined by the impedances in the arms of the bridge. For a definite frequency, the bridge is balanced and no movement of the control shaft 10 is effected, whereas for other frequencies the bridge is unbalanced and the shaft 10 is rotated in a sense depending upon the sense of unbalance.

A turbine or other source of power, or generically a rotating system, T, drives the alternating current generator or source A related to the bridges of Figs. 1, 3 and 4. The source A in this instance may be a small alternating current generator driven by the rotary structure T through the shaft 44, or it may be an alternating current generator of large capacity for supplying current to any suitable load connected to the supply circuit conductors 45 and 46, in which case the frequency or speed of T and A may be controlled by controlling the opening of the valve V controlling the rate of supply of motive fluid or steam through the pipe 47 to the turbine T. In this case the brush 35, with contacts 33 and 34, controls the reversible electric motor M1 receiving current from any suitable source, as 48. When the disc 32 is in the position indicated in Fig. 1, the motor M1 is deenergized, and this condition corresponds with the position of balance of the Wheatstone bridge. Should the bridge be unbalanced, the galvanometer needle 19 is deflected, causing rotation of shaft 10 to an extent corresponding with the extent of unbalance, the contact 33, for example, will be brought into engagement with the contact 36, energizing the motor M which runs in a certain direction, rotating the shaft 49, through any suitable great gear reduction, generally represented by the pulleys 50, 51 and belt 52, thereby causing the member 53 to advance upwardly along the threaded shaft 49, carrying the abutment 54 upward.

ly, with resultant tendency to compress the spring 55, which opposes the fly ball governor 56, driven by the turbine or device T, to partially actuate the valve V, changing 5 the speed or frequency.

The controller mechanism is similar to that described in U. S. patent to Leeds No. 1,125,699.

Thus far described, the position of member C depends solely upon the frequency of 10 current generated by the alternator A. That feature is claimed in copending application Serial No. 18,794 filed March 27, 1925, and is not, per se, the invention herein claimed. 15 Referring to Fig. 3, unit No. 1 is an apparatus comprising a self-balancing bridge of the type described except that resistances r_{12} and r_{13} have been omitted. This control unit serves to maintain the frequency of 20 the alternator associated therewith at a desired value in any desired manner, for example, by controlling the flow of steam to a turbine coupled thereto. The specific circuit and control arrangement is more fully 25 described in the aforesaid copending application. It is to be understood that the speed of this unit may be controlled in any other suitable or satisfactory manner or with other apparatus, as in the features of my invention involving this unit, the specific manner 30 in which speed control is effected is immaterial and the foregoing is for the purpose of explanation only.

Reverting to Figs. 1, 4 and unit No. 2 of 35 Fig. 3, when the contact 2 is moved manually along resistance r_{13} , the constants of the second and fourth bridge arms above identified are altered and the contacts 3 and 4, mounted on member C, assume a new position 40 of balance for any given frequency; in effect, the calibration of the apparatus has been changed.

By observing the indication of a watt meter and shafting the position of contact 2 45 along resistance r_{13} , an operator may alter the characteristic load-frequency curve of the unit comprising alternator A and turbine T, or their equivalents, so that instead of being of the steadily drooping nature as 50 hereinafter explained, it may be of any desired shape. It is more desirable, however, only to effect a rough control in such manner and to change the calibration in a manner now described.

55 The current and voltage coils of a watt meter W are connected, respectively, in the conventional manner, in series with, and in shunt to, the output circuit of the alternator A. A shaft 57, driven by the movable element 60 of the watt meter through suitable mechanism, as, for example, gear 58, gear sector 59 and shaft 60, moves the contact 1 along resistance r_{12} so that the amount of power supplied by alternator A uniquely 65 determines the position of contact 1 and there-

fore to a predetermined extent affects the calibration of the apparatus. Consequently, for any given frequency, the point of the balance of the bridge or the position of contacts 3 and 4, depends upon the load carried by 70 the alternator.

It is to be understood that the extent of movement of contact 1 may bear any desired relation to the extent of movement of the rotatable element of the watt meter and, further, that the ratio between the increments of movement of the movable contact 1 and the rotatable or movable watt meter element may vary throughout the range of movement. As before stated, the resistance r_{12} may be constructed so that equal increments of movement of contact 1 result in either equal or unequal changes of resistance. By suitably designing the mechanical connections between the movable element of the watt meter, or suitably constructing resistance r_{12} , or both, calibration of the apparatus may be changed to any desired extent for a change from a given load to another given load and, further, the calibration may be affected to different extents by equal increments of load throughout the range of the apparatus. The speed-load curve of the moving system will, as explained hereinafter, be correspondingly modified.

For the purpose of explanation, it will be assumed that in Fig. 1 the frequency and load are normal. If the load is increased, there will be a fall in the frequency which unbalances the bridge, causing a current to flow through galvanometer coil 20, deflecting needle 19 and effecting a movement of control shaft 10 through the mechanism above described. The degree of unbalance is determined not only by the change in frequency, but also by the change in position of contact 1, due to the increased load, such change in position of contact 1 being proportional in amount to the increment of load increase and being in such direction that balancing of the bridge occurs at a frequency lower than normal.

Contact 33 on control 32 is brought into engagement with fixed contact 35, closing the circuit of reversible motor M1, to operate valve V, in such a sense to permit an increased flow of steam to turbine T, tending to increase the speed of T and the frequency of the output of A.

The lower frequency attained when the bridge is balanced for the new position of contact 1 as effected by watt-meter W, is maintained by the control mechanism as above described for normal load and frequency until the load again varies or the contact 2 is manually adjusted. As the controller does not tend to maintain the frequency constant irrespective of load but varies with load, it will be termed, for the pur-

pose of convenience, a "load-biased frequency controller".

Referring to Fig. 4, the bridge circuit is identical with that of Fig. 1, except that the 5 resistance r_{12} and contact 1 have been omitted. In this form of my invention, the calibration of the apparatus is not affected by the alternator so that, if desired, a chart 42 may record directly in terms of frequency or 10 revolutions per unit of time, provided that the position of contact 2 remains unchanged. The contact 2 may be provided with a scale so that if moved, a definite indicated correction may be added or subtracted from recorded frequency.

To effect a modification of the load-speed curve, the movable element of the watt-meter W changes the position of contact 35' with respect to contacts 33, 34, carried by the control disc 32 through any desired connecting mechanism. If an arrangement as shown in Fig. 1, for moving contact 1, is used, the extent of movement of contact 35' is in direct proportion to movement of the load element.

25 By utilizing an arrangement as in Fig. 4, in which the watt-meter shaft 57 drives a cam 61, which may be replaced by a cam of different contour, or which is itself of adjustable configuration, in engagement with a cam 30 follower 62, connected to shaft 63, on which contact 35' is fixedly attached, and by properly designing or adjusting the shape of cam 61, it is possible to secure a load-speed curve of a desired outline.

35 When the control disc 32 and contact 35' are in the position shown in Fig. 4, the frequency of, and the load upon, alternator A are normal. Upon increase of load, the line frequency drops unbalancing the bridge and 40 effecting movement of control shaft 10. Simultaneously the contact 35' is rotated by the movable element of watt-meter W to an extent determined by the increase of load, the mechanical connections including cam 61 be-

45 tween the contact and the watt-meter element, etc. The circuit through motor M1 is completed and as above described, the valve V is operated to tend to increase the speed of turbine T. The lower frequency attained when

50 the bridge is balanced for the new position of contact 35' as effected by watt-meter W, is maintained substantially constant until the load again varies or contact 2 is manually or otherwise adjusted. This type of controller

55 is also conveniently termed a "load-biased frequency controller". The same controller may be utilized simultaneously to control a plurality of alternators by having shaft 10 rotate a corresponding number of control 60 discs 32 each co-acting with a contact 35' whose position is determined by the load upon the alternator associated therewith.

In Fig. 3, the alternators A, A1, and A2, located at the same or isolated points are connected in parallel to circuit 45, 46, each of

which is driven by a prime mover whose speed is controlled, as turbines T, not disclosed in this figure but similar to that to left of line B-B in Fig. 1. Control unit No. 1 associated with alternator A1 is a normal or 70 simple frequency controller, as described hereinbefore and in the aforementioned application, whereas control units 2 and 3, associated with alternators A and A2, respectively, are load-biased frequency controllers 75 or controller-recorders.

The contact 1 of Figs. 1 and 3 or the contact 35' may, as above described, in each of the control units produce unequal increments of biasing effect upon the alternator system, 80 for equal increments of change of load to modify the shape of the characteristic load-response curve in a desired manner, or the increments of biasing effect may bear a linear relation to the change of load. For example, 85 curves a and a_2 of Fig. 6 are lines of different but constant slope, whereas in curve a_3 regions of slight slope are connected by a short portion of great slope.

Assuming that all alternators connected 90 to the line are load-biased, as A and A2, the system load may be distributed between the individual machines in a desired manner by suitably modifying the load-speed curve of the units. Obviously two or more alternators 95 operating in parallel have the same frequency and the distribution of load between the machines and the line frequency will depend upon the characteristics of all machines as

produced by the load-biased frequency controllers. For example, referring to Fig. 7, in which lines a and a_2 represent, respectively, the load-frequency curves of alternators A and A2 when the system load is L_1 , alternator A carries the entire load, the frequency under 100 this condition being f_1 ; when the system load increases, so that, for example, the frequency is f_2 , alternator A carries load L_2 and alternator A2 carries load L_3 , the system or station load being, of course, the sums of loads 105 L_2 and L_3 . The alternator A under the last condition carries the larger part of the system load but when the total load increases to a value that the frequency decreases to a value f_3 , alternator A2 carries the large part 110 L_5 of the load and alternator A the remainder. It is a feature of the arrangement that the load on the individual alternator is a function of the total load.

The load-frequency curves of systems of inherently different characteristics are substantially identical when associated with controllers of practically similar predetermined characteristics. 115

When an alternator is provided only with simple frequency control, as alternator A1, Fig. 5, and another or other alternators are load-biased, as A and A2, under normal conditions alternator A1 is able to maintain the predetermined frequency and the individual 120 loads upon the load-biased machines remain 125 130

unchanged and are represented by L6 and L7. If the system load is so great that the additional load cannot be supplied by alternator system A1, the frequency control is ineffective and the frequency falls permitting the load-biased machines to take on additional load at the expense of system frequency. Upon restoration of normal conditions, the excess load is shifted back to alternator A1 having simple frequency control. The load upon the load-biased machines can, of course, be changed by changing the calibration of the bridge circuit, i. e. by shifting contact 2 along resistance r13.

15 It is to be understood that my invention is not limited to turbo-alternator systems, or electrical power systems generally.

What I claim as my invention is:

1. A system comprising a movable member, 20 driving means therefor, means adjustable to vary the speed of said driving means, means responsive to the speed of said member, means responsive to the load upon said member, and governor means responsive to the speed of 25 said driving means to control said adjustable means, affected by said load responsive means and said first speed responsive means.

2. An alternating current supply system 30 comprising a group of alternators operating in parallel, driving means for each alternator, a plurality of means each adjustable to vary the input energy to one of said driving means, means responsive to system frequency for regulating one of said adjustable means 35 whereby the associated alternator carries the normal increases of system load and maintains the system frequency constant despite said normal increases of load, and a plurality of means each responsive to system frequency 40 and the individual load upon one of the alternators to regulate the other adjustable means whereby increases in load in excess of maximum normal increase are shared by said other alternators and the system frequency held 45 constant at a subnormal value determined by the system load.

3. An alternating current supply system 50 comprising a group of alternators operating in parallel, driving means for each alternator, means adjustable to vary the speed of each of said driving means, a plurality of means each responsive to the system frequency, a plurality of means each responsive to the load upon an alternator of said group, 55 and a plurality of speed-responsive means for regulating the speed adjusting means of said alternators, and each controlled jointly by one of said frequency responsive means and one of said load responsive devices.

60 4. An alternating current supply system comprising a group of alternators operating in parallel, driving means for each alternator, means adjustable to vary the input energy to said driving means, and a control system for 65 effecting a predetermined distribution of load

between said alternators and a predetermined redistribution of load upon a change in system frequency irrespective of the load-speed characteristics of said units comprising means responsive to the system frequency for controlling each of said adjustable means, and means responsive to the loads upon the individual alternators to modify in accordance with a predetermined load-frequency characteristic the frequency control upon each of 75 said adjustable means to effect a predetermined relation between the individual alternator loads for each different system frequency.

5. In a system of the character described, 80 apparatus forming part of said system, and means providing for control of said apparatus in accordance with the joint effect of speed conditions of said system and load conditions with respect to said apparatus; said 85 control means including a galvanometer having an element movable to different positions from a given position, and means associated with said element and operable in accordance with the degree of departure of the same 90 from said given position.

6. In a system of the character described, 95 apparatus forming part of said system, and means providing for control of said apparatus; said control means including a balanced electrical circuit, means providing for unbalancing of said circuit in degree corresponding to changes in load conditions on said apparatus, and means providing for unbalancing of said circuit in degree corresponding to 100 changes in speed conditions of said system.

7. In a system of the character described, 105 apparatus forming part of said system, and means providing for control of said apparatus in accordance with speed conditions of 110 said system and load conditions with respect to said apparatus, said means including a Wheatstone bridge.

8. In a system of the character described, 115 apparatus forming part of said system, means operable to control said apparatus in accordance with the joint effect of speed conditions of said system and load conditions with respect to said apparatus, and cam means forming part of said control means.

9. In a system of the character described, 120 an electrical distribution line, a dynamo electrical machine connected to said line, and means providing for control of said machine; said control means including a balanced electrical circuit, means providing for unbalancing of said circuit in degree corresponding to changes in load conditions on said machine, and means providing for unbalancing of said circuit in degree corresponding to changes in 125 speed conditions of said system.

10. A system comprising an alternator, driving means therefor, means adjustable to vary the speed of said driving means, a 130 governor driven by said driving means and

controlling said adjustable means, and means jointly responsive to the speed of the alternator and to the load thereon to vary the setting of said governor.

11. A system comprising an alternator, driving means therefor, a governor driven by said means for controlling the speed thereof, an electro-mechanical system controlling the setting of said governor and responsive to changes in frequency from a predetermined frequency, means manually adjustable to determine the frequency at which said electro-mechanical system is balanced, and means responsive to the load of said alternator for changing the frequency at which said electro-mechanical system is balanced.

12. An alternating current supply system comprising a group of alternators operating in parallel, driving means for each alternator, governors driven by said driving means for controlling the input energy supplied thereto, and means for changing the governor settings for different values of total load to effect for each value thereof a predetermined distribution of load between the alternators of said group comprising a plurality of electro-mechanical systems each varying the setting of the associated governor when the frequency is other than a predetermined frequency at which the electro-mechanical system is balanced, and a plurality of means each responsive to the load of an alternator for varying the frequency at which the associated electro-mechanical system is balanced.

13. An alternating current supply system comprising an alternator, and means for controlling said alternator comprising a balanced electrical circuit, means for varying the input energy to said alternator when the system frequency is other than the frequency at which said circuit is balanced, and means responsive to the load upon said alternator for varying the frequency at which said circuit is balanced.

EDGAR D. DOYLE.
